UNITED STATES PATENT OFFICE.

HENRY J. BROWER, OF BROOKLYN, NEW YORK, ASSIGNOR TO THOMAS H. MCALLISTER, OF SAME PLACE.

DISSOLVING-KEY FOR OXYHYDROGEN LIGHTS.

SPECIFICATION forming part of Letters Patent No. 330,092, dated November 10, 1885.

Application filed March 16, 1885. Serial No. 159,103. (No model.)

To all whom it may concern:

Be it known that I, HENRY J. BROWER, of Brooklyn, in the county of Kings and State of New York, have invented a new and Improved Dissolving- Key for Oxyhydrogen Lights, of which the following is a full, clear, and exact description.

The object of my invention is to provide a new and improved key for oxyhydrogen lights, which key is to be used for turning gas from one jet to one or more other jets, and producing the so-called "dissolving" effects, or to be used in any other case in which it may be necessary to transfer the gases.

The invention consists in the combination, with a cock or key body having separate channels for the oxygen and hydrogen, of a valve-plug in each channel, which valve-plugs are connected to operate together.

Reference is to be had to the accompanying drawings, forming part of this specification, in which similar letters of reference indicate corresponding parts in all the figures.

Figure 1 is a plan view of a double oxyhydrogen light provided with my improved key. Fig. 2 is a plan view of my improved dissolving-key. Fig. 3 is a cross-sectional view of the same, taken on the line α α of Fig. 2. Fig. 4 is a sectional view of the same, taken at right angles to the plane of the section of Fig. 3. Fig. 5 is an enlarged detailed section through one of the central plugs, showing the aperture of the same connecting with the hydrogen passage.

From the body A of the cock or key the nipples B' B² and C' C² project, the nipples B' and C' being connected with the tubes leading the gas to one oxyhydrogen-burner, D', and the nipples B² and C² being connected with the tubes leading the gas to the other oxyhydrogen-burner, D². The hydrogen is conducted through the pipe E' from the tank F' into the body A, and the oxygen is conducted from the tank F² through the pipe E² into the said body. In the middle of the body the two tapering bores G' and G² are arranged which contain the plugs H' and H², respectively. The bore G' is connected by a channel, I', with a neck, to which the pipe E' is coupled, and the bore G² is connected by a channel, I²,

with a neck, to which the pipe E² is coupled, so that the hydrogen can pass into the bore G' and the oxygen into the bore G². The bores G' and G² are not connected. Channels J' and J² connect the nipples B' and B² with the bore G², and channels K' and K² connect the nipples C' and C² with the bore G', which channels J' J² K' K² can be closed by the plugs L' L² M' M², respectively, and entirely independently of each other. The plugs H' and H² are hollow, and are provided with apertures, which register with the channels I' and I², respectively, and with opposite apertures, m, which register with the channels J' J² or K' K², as shown in Figs. 3 and 4. A handle-lever, N, is connected with one plug—for instance, H²—and is connected by a link, O, with a lever, P, projecting from the plug H' and parallel with the lever N, so that when the lever N is in the position shown in Fig. 1 the oxygen and hydrogen can pass from the bores G' G² through the channels J' J² and K' K², the hydrogen passing through the channels I' K' K² and the oxygen passing the channels I² J' J². Under no circumstances can the oxygen and hydrogen mix in the body A of the key.

When the lever is swung into the position shown in Fig. 2, the plugs H' and H² are in such a position that all the oxygen and almost all the hydrogen pass to the lamp D², a small quantity of hydrogen passing through the lamp D', so that the flame cannot be extinguished.

When the lever N is swung in the position shown in dotted lines in Fig. 1, all the oxygen and almost all the hydrogen are admitted to the lamp D', the oxygen is cut off from the lamp D², and but a very small quantity of the hydrogen passes to the lamp D² to keep up the flame.

Having thus described my invention, I claim as new and desire to secure by Letters Patent—

1. The combination, with the body of a dissolving cock or key having independently arranged three-way passages, of the independent plugs, each having apertures to connect with the passages of the three-way passage which it controls, substantially as and for the purpose set forth.

2. The combination, with the body of a dissolving cock or key having separate channels for the oxygen and hydrogen, of a plug in the oxygen-channel and a separate plug in the hydrogen-channel, and of levers for connecting the plugs to operate together, substantially as herein shown and described.

3. The combination, with the body of a dissolving cock or key having separate channels for the oxygen and hydrogen, of a plug in the oxygen-channel and a separate plug in the hydrogen-channel, a bar projecting from each plug, and a link connecting the said bars, substantially as herein shown and described.

15 4. In a dissolving cock or key for oxyhy-

drogen lights, the combination, with the body A, having the transverse oxygen-channels $J' J^2$, the transverse hydrogen-channels $K' K^2$, the oxygen-channel I^2 , connected with the channels $J' J^2$, and the hydrogen-channel I' , connected 20 with the channels $K' K^2$, the plugs H^2 and H' at the junctions of the channels J' , J^2 , and I^2 , and $K' K^2$ I' , respectively, and of levers for connecting the plugs, substantially as herein shown and described.

HENRY J. BROWER.
